ATTORNEY

UNITED STATES PATENT OFFICE.

EUGENE R. WEBER, OF ROCHESTER, NEW YORK.

CORK-EXTRACTOR.

1,219,510.

Specification of Letters Patent. Patented Mar. 20, 1917.

Application filed March 24, 1916. Serial No. 86,464.

To all whom it may concern:

Be it known that I, EUGENE R. WEBER, a citizen of the United States, residing at Rochester, in the county of Monroe and State of New York, have invented certain new and useful Improvements in Cork-Extractors, of which the following is a specification:

This invention relates to a cork extractor and has for its object to provide a very simple, cheap and efficient device of the kind, one of which will be inserted in each cork placed in a bottle for sealing the same and disposed of with the bottle and its contents.

Another object of the invention is to provide a cork extractor of the type described which when applied to the cork of a sealed bottle and in position to be placed upon the market, the extracting arms will lie closely against the sides of the mouth of the bottle and out of the way, but which may be readily raised into position for use to provide a strong lever for withdrawing the cork.

Another object of the invention is to provide a cork extractor with folding handles and so shaped that when applied to a sealed bottle, the portions above the mouth of the bottle will lie but little above the plane of the top thereof while the ends of said handles will bear snugly against the sides of the bottle neck, and being provided with openings in these ends the same may be used for passing the sealing wire therethrough to secure a cover or cap over the mouth of the bottle and over the extractor as well.

Other objects of the invention not hereinabove specifically pointed out will be set forth in the following specification and illustrated in the drawings accompanying the same in which:

Figure 1 is a vertical section through the mouth of a bottle sealed with a cork and the improved extractor applied thereto in the manner in which it will be found on the market.

Fig. 2 is an elevation of the cork extractor with the withdrawing handles in elevated position, and,

Fig. 3 is a perspective view of one of the withdrawing handles.

Referring to the drawings in which similar reference characters designate corresponding parts throughout the several views A indicates the mouth of a bottle and B a cork inserted therein. 10 is an ordinary

cork screw made of wire on the upper end of which is an elongated eye 11 that lies in a direction at right angles to the axis of the cork screw. The top portion 12 of the eye 11 is straight and forms a pintle for the hinged ends 13 of two swinging handles 14, 15 by means of which the cork is withdrawn from the bottle.

The handles 14 and 15 are alike each being of a substantially right angular form to lie when closed against the top and sides of the mouth of a bottle. Each handle is made of stout sheet metal with fingers at one end bent into circular form to embrace the portion 12 of the eye 11 of the cork screw. The bent fingers of the two handles form a hinge and interengage. From the hinge 13 each handle extends outwardly, when in position on a bottle, in a horizontal direction to the outer edge thereof and then bends downwardly against the side, lying close thereto and turns inwardly and outwardly at the end with a short curve just below the enlargement formed on the mouth of bottles. Through the openings 16 in the ends of the handles 14, 15 may be threaded a wire 17 for sealing the bottle, said wire may also hold a cap or thin metal cover 18 over the mouth of the bottle and the extractor when in folded position thereof.

When a cork is to be withdrawn the sealing wire 17 if there be one about the bottle, is severed, the cap 18 broken or removed and the arms 14, 15 raised into position shown by dotted lines in Fig. 1. When thus opened the ends 13, 20 of the respective arms 14, 15 will lie in substantially a horizontal position with the portions of said handles connecting them to the eye 11 of the cork screw standing vertically. In this position an excellent hand grip is provided and the cork may be extracted with little effort.

The simplicity of the device, the fewness of the parts and the cheapness of manufacture enable a manufacturer of bottled commodities to give away an extractor with each bottle and thus provide the consumer with a ready means for withdrawing the cork.

While the form of the device herein shown is the best known to me at the present time, it is to be understood that various changes and modifications may be made therein provided they fall within the terms of the claims.

What I claim as new is:—

1. A cork extractor comprising a worm-shaped portion having an elongated eye at its upper end and two angled arms hinged thereto and adapted when applied and out of use to lie across the top and against the sides of a mouth of a bottle and to be swung into contact to form a T-shaped handle for use in withdrawing the cork.
- 10 2. A cork extractor comprising a worm-shaped portion having an elongated eye at its upper end extending perpendicularly to the axis of the worm-shaped portion, a pair of angled arms made of flat metal hinged 35 on said eye, and independently movable, said arms each being shaped substantially to the outline of the mouth of a bottle to lie closely against the same and to be brought into contact to form a T-shaped handle for 40 extracting the cork.
- 20 3. A cork extractor comprising a worm-shaped portion to engage a cork, a pair of right angled arms each hinged thereto at one end and adapted when out of use with the worm portion in the cork to lie over 25 the top and snugly against the sides of the mouth of a bottle, and to be folded upwardly into contact with the angled ends extending in opposite directions to form a handle for withdrawing the cork.
- 30 4. A cork extractor comprising a worm-shaped portion to engage a cork and having an elongated eye at its upper end, and a pair of angular arms each hinged to said eye and adapted to be folded over the mouth 35 of a bottle when the worm is screwed into a cork and so shaped as to lie closely against said mouth and the sides of the same with inturned terminal ends fitting beneath the shoulder of the bottle neck and having 40 means for attaching a fastener to said ends.

In testimony whereof I affix my signature in presence of two witnesses.

EUGENE R. WEBER.
